POURING LIP FOR PAINT CANS

Harold P. Gray, Traverse City, Mich.

Application June 18, 1953, Serial No. 362,453

1 Claim. (Cl. 222—570)

2

to overhang the mouth of the pail 5 and to drain back into the pail any accumulations of paint running down the interior surface 9 of the length of strip applied to the pail.

5 A similar flange 11 is applied to the outer face 12, desirably at the extreme top edge of strip 7 and constitutes a pouring lip. This flange 11 desirably tapers to an extreme thin pouring edge so that little or no drip therefrom will occur following completion of a pouring operation.

In practice, when a length of strip 7 is applied to the sealing channel of a pail as shown in Fig. 2, there will be no occasion for any paint to run down the outside of the can following a pouring operation, nor will any such paint normally reach the sealing groove or channel 6 to accumulate therein.

Despite the fact that the device is rather flexible, being made of rubber or plastic or the like, it becomes semi-rigid when applied to a pail, this being due in part to the arc into which it must be formed when applied to the sealing groove and is partly attributable to the fact that the strip is relatively narrow as compared with oscillatory spouts heretofore proposed. Because of its semi-rigidity, the attachment constitutes a convenient means of wiping excess paint from the brush. If the painter, instead of wiping his brush against the top rim of the pail, uses the top edge of the strip 7 for this purpose, the surplus paint will be guided by the flange 10 over the sealing groove and back into the pail. In any event, the lower edge portion 8 of the strip effectively fills the sealing groove throughout that portion of it in which such edge is wedged.

I claim:

35 A pouring spout attachment for application to cylindrical pails having tops and curved sealing channels having inner and outer walls and an outer rim, such attachment comprising an elastically deformable strip of flexible material of sufficient length to extend about the pouring margin of a pail and of substantially uniform cross section throughout its length, said strip being provided with inner and outer faces, the outer face being continuously provided substantially at its extreme upper margin with a transverse pouring flange with an outwardly projecting free edge adapted to overhang but dimensioned to be spaced above the can rim, said inner face being provided intermediate its upper and lower margins with an inwardly directed drain flange having an inwardly extending free edge, the lower margin of the strip being dimensioned to be wedged into the sealing channel of a paint pail with the drain flange overlapping the inner wall of the sealing channel to return pail contents to the pail without fouling said channel, said strip being adapted to extend upwardly from the pail top with its inner and outer faces constituting upward extensions of the inner and outer walls of the sealing channel.
